UNITED STATES PATENT OFFICE

132,054

DESIGN FOR A CONCRETE BURIAL VAULT COVER

Wilbert W. Haase, Forest Park, Ill., assignor to
Wilbert W. Haase Co., Forest Park, Ill., a cor-
poration of Illinois

Application November 20, 1940, Serial No. 96,709

Term of patent 14 years

To all whom it may concern:

Be it known that I, Wilbert W. Haase, a citizen of the United States of America, residing at Forest Park, in the county of Cook and State of Illinois, have invented a new, original, and ornamental Design for a Concrete Burial Vault Cover, of which the following is a specification, reference being had to the accompanying drawings, forming a part thereof.

Referring to the drawings:

Figure 1 is a plan view of a concrete burial vault cover embodying my new design.

Fig. 2 is a side elevational view of the cover shown in Fig. 1.

Fig. 3 is an end elevational view of the cover shown in Fig. 1.

Fig. 4 is an enlarged view of a portion of the vault cover and one of the handles thereof; and,

Fig. 5 is a similar view of the corner portion shown in Fig. 4.

The characteristic features of my design reside in the specific configuration and arrangement of the handles in association with the specific configuration of the concrete burial vault cover, all as shown.

I claim:

The ornamental design for a concrete burial vault cover, as shown and described.

WILBERT W. HAASE.
